[57] **CLAIM**

The ornamental design for a combined water sensor and alarm apparatus, as shown and described.

DESCRIPTION

FIG. 1 is a perspective view including the top and one side of a combined water sensor and alarm apparatus showing my new design;

FIG. 2 is a top plan view thereof on an enlarged scale; FIG. 3 is a side view thereof on an enlarged scale showing the side included in FIG. 1, the opposite side view being substantially a mirror-image thereof;

FIG. 4 is a partial sectional view thereof on an enlarged scale taken substantially on section line 4—4 of FIG. 2; and,

FIG. 5 is a partial sectional view thereof on an enlarged scale taken substantially on section line 5—5 of FIG. 2. The bottom of the combined water sensor and alarm apparatus is substantially plain and unornamented.

Fig. 4.

Fig. 5.
